APPARATUS FOR MANUFACTURING PAPER

Filed Oct. 31, 1928

UNITED STATES PATENT OFFICE

TOM HARVEY, OF MIDDLETOWN, OHIO

APPARATUS FOR MANUFACTURING PAPER

Application filed October 31, 1928. Serial No. 316,276.

My invention relates broadly to the paper making art, and specifically to a novel process for determining the width of a paper web during its formation by means of shower deckles in which the vat solution is used instead of fresh water.

In the prior art it has long been suggested that a simple means for controlling the width of the sheet is by the provision of spray of fresh water so directed at the side edges of the sheet as to wash away the pulp leaving a definite edge. Cronk, in his Patent No. 152,216, issued June 23, 1874, shows such an arrangement, and this patentee further suggests the use of adjustable sprays which will permit the position of the application of the spray to be changed so that the width of the sheet may be varied.

Cronk and all the other patentees who have provided different modifications of his original idea used fresh water. This has led to many difficulties. In the first place, to keep the pulp within the feed box or vat in proper condition it is necessary to maintain the mass of pulp at a proper acidity as determined ordinarily by a pH test. If shower deckles using fresh water are used, the strength of the solution is being constantly varied, which affects the acidity of the pulp in the vat. Further, the more fresh water which is added, the more water which needs to be removed from the pulp.

It is the object of my invention to provide a shower deckle which will permit the water or solution which is withdrawn from within the cylinder mold to be used again to define the border edges of the web. It is further specifically my object to provide preferably an adjustable shower deckle which will be so constructed that it will not tend to block up.

The above and other advantages in the simplicity of the arrangement and mechanical construction of the shower deckle which I propose to use, I accomplish by that certain combination and arrangement of parts of which I have shown a preferred embodiment.

In the drawings:

Figure 1 is a side elevation of my preferred type of shower deckle.

Figure 2 is an end elevation of the deckle

nozzle showing the discharge passage which produces a confined sheet-like spray.

Figure 3 is an end elevation of the complete assembly shown in Figure 1.

Figure 4 is a diagrammatic view showing how my process may be carried out.

Referring first to the diagram in Figure 4, I have indicated the pulp vat at 1 with a cylinder 2 having a cylindrical wall of screen-like material 3 through which the pulp solution is withdrawn, leaving the pulp on the outer surface of the screen to be picked up by the felt. The general arrangement of cylinder mold illustrated is that which is well known in the art.

The cylinder may be driven by a suitable pulley, and the ends 4 of the cylinder have a pipe connection 5 to permit the solution to be pumped away from within the cylinder by a pump 6 having a delivery pipe 7. From the pipe 7 pipes 8 and 9 extend to the shower deckles, one at each end of the cylinder.

My shower deckle is composed of an outer tubular member 10 within which an inner pipe section 11 is adjustably secured. A packing nut 12 and packing 13 prevents leakage of the liquid pumped through the annular space between the outer member 10 and the inner pipe 11. The tubular member 10 has a projecting nozzle-like portion 14 which has a slot 15 therein which may, for example, be one eighth inch wide and which, at the ends, has straight walls 16. The outer tubular member has a boss 17 within which the end of an adjustment bolt 17^a is secured. The adjustment bolt 17^a extends from the boss 17 through an aperture in a boss 18 which is formed in a housing 19 which is mounted on the exterior of the pipe 10. The adjustment bolt is provided with a wing nut 17^b, the turning of which moves the outer tubular member with relation to the inner pipe. Liquid is supplied to the deckle through a bushing 20 which is secured to the end of the inner pipe 11.

I have further shown a boss 21 formed on the housing 19 which may, as indicated, provide an attachment by which the deckle may be supported. As the liquid is pumped through the bushing into the pipe 11 it passes

to the open end 21 of the pipe. Passing out the open end of the pipe, the flow of the liquid is directed downwardly to the nozzle slot which, being of suitable length, causes the liquid to be ejected in a solid sheet instead of 5 a splashing spray-like formation.

In Figure 1 I have indicated the cylinder mold at 2 with the web forming thereon at 22. The sheet of liquid which determines the 10 edge of the web is indicated at 23. It will be apparent that when it is desired to make the paper web narrower all that needs to be done is to turn the wing nut and the casing 10 will be moved to the left as indicated, thereby 15 forming a wider sheet of water which will move the edge of the web also further to the left.

Modifications in the particular type of 20 deckle which I have disclosed will occur to those skilled in the art. As far as I am aware no one has previously utilized a nozzle having a discharge orifice of such size that the exhausted liquor from the vat might be used for a shower deckle. It will be apparent that 25 should a nozzle with fine spray holes be used that the holes would almost immediately become blocked up.

Having thus described my invention, what 30 I claim as new and desire to secure by Letters Patent, is:—

1. A shower deckle comprising an outer tubular member slidably mounted on an inner tubular member, said inner tubular member having an open end, said outer tubular 35 member having a nozzle with an elongated discharge passage therein, and means for supplying liquid to said inner member.

2. A shower deckle comprising an outer tubular member slidably mounted on an inner tubular member, said inner tubular member having an open end, said outer tubular member having a nozzle with an elongated discharge passage therein, and means for supplying liquid to said inner member, and 45 means for regulating the position of the outer tube with relation to the inner tube.

3. A shower deckle comprising an outer tubular member slidably mounted on an inner tubular member, said inner tubular member having an open end, said outer tubular member having a nozzle with an elongated discharge passage therein, and means for supplying liquid to said inner member, the extent of said discharge passage being greater 50 than the range of movement of said outer member.

4. In combination, a shower deckle having a tubular outer body having an extension within which an elongated slot is formed 60 which provides a discharge nozzle, an inner tubular member having an open end through which liquid is forced, a packing gland between the outer body and inner tubular member, and means for causing relative movement 65 between the outer body and inner member.

5. In combination, a shower deckle having a tubular outer body having an extension within which an elongated slot is formed which provides a discharge nozzle, an inner tubular member having an open end through which liquid is forced, a packing gland between the outer body and inner tubular member, and means for causing relative movement between the outer body and inner member, the slotted portion of said extension controlling the extent of the spray in accordance with the position of the end of said inner tubular member.

TOM HARVEY.
